UNITED STATES PATENT OFFICE.

HENRY C. SERGEANT, OF WESTFIELD, NEW JERSEY, ASSIGNOR TO THE INGERSOLL-SERGEANT DRILL COMPANY, OF NEW YORK, N. Y.

MINING-MACHINE.

SPECIFICATION forming part of Letters Patent No. 683,864, dated October 1, 1901.

Application filed January 29, 1901. Serial No. 45,202. (No model.)

To all whom it may concern:

Be it known that I, HENRY C. SERGEANT, a citizen of the United States, and a resident of Westfield, in the county of Union and State 5 of New Jersey, have invented a new and useful Improvement in Mining - Machines, of which the following is a specification.

This invention relates generally to that class of mining-machines which may be used 10 in various mining operations, but are especially adapted for the mining of coal and known as "coal-picks," such a machine embodying a cylinder and a tool-carrying piston mounted on wheels and adapted to be run 15 from place to place and toward its work by hand. The improvement relates particularly to brakes applied to the wheels of such a machine to prevent them from running backward; and it consists in the brake mechanism 20 ism hereinafter described and claimed which permits the machine to be easily run forward, but which acts automatically to prevent it from running backward.

Figure 1 represents a side view of a mining- 25 machine embodying my invention; Fig. 2, a rear view of the same; and Fig. 3, a detail view, which will be hereinafter explained.

Similar letters and numerals of reference 30 designate corresponding parts in all the figures.

a is the drilling-cylinder, fitted with a piston, (not shown,) and the piston-rod *b* of which is furnished with a chuck *c*, which carries the drill or pick *d*. This cylinder may be furnished with a valve of any suitable kind for 35 controlling the operation of its piston and is provided on its side with trunnions *e*, which form the axles of the wheels *f*, on which the machine is supported. Attached to each side 40 of the cylinder is a handle *g*.

g is a rock-shaft, to which are fixedly attached the upwardly-projecting brake-dogs *h*, of which there is one represented for each wheel. This rock - shaft, which is parallel 45 with the axis of the wheels *f*, is fitted to rock in bearings in the ends of radius-bars *i*, which are pivoted in any suitable manner to the ends of the trunnions, centrally to the latter, as indicated at *j*. The said rock-shaft, which 50 may be termed the "brake-shaft," is also furnished with loose rollers *j*, adapted to run on

the ground or on the same surface on which the wheels *f* run, the length of the said bars *i* being such that when the said rollers *j* are on the ground or floor the rock-shaft is under 55 the rear portions of the wheels *f*. At one side of the cylinder a hand-lever *k* is provided on the rock-shaft, and this lever is connected with one of the trunnions *e* by a spring *m* in any suitable manner, the said spring being 60 represented (see Fig. 1) as connected with the lever by a hook *n* and with the trunnion by a ring or yoke *o*, which is shown detached in the side view, Fig. 3, encircling the trunnion. The said lever is also connected with the yoke *o* by a rod *p*, which is pivoted at its rear end to the lever and connected at its front end with the yoke *o* by a pin *q*, affixed to the yoke and passing through a slot *r* in the rod. This slot permits the drawing back of the lever to 70 an extent sufficient to withdraw the brake-dogs from the wheels, but serves as a stop to limit this backward movement. The position of the dogs when in contact with the wheels is such that a line drawn through the center of 75 the brake-shaft and through any point of contact between the dog and the rim of the wheel will form an acute angle with the portion of the rim below said point of contact. The spring *m* always tends to draw forward the brake-dogs 80 against the rims of the wheels; but when the machine is pushed or run forward by the handles *g* the friction between the wheels and the dogs tends to throw off the dogs, so that they present little or no obstacle to the 85 forward movement; but on the recoil of the machine or its tendency to "kick back" or in case of any accidental tendency of the wheels to turn backward the friction between them and the dog is such as to draw the dogs toward 90 the wheels, and so to chock them. On pulling back the lever by hand the dogs are withdrawn from the wheels and the machine is free to run backward. For running back the machine the operator may with one hand 95 pull back the lever as far as permitted by the stop-pin *q* and then pull back with that hand remaining on the lever and the other hand on the handle *g* on the other side of the machine. The rod *p* by limiting the backward 100 movement of the lever prevents the over-straining of the spring.

Although I have shown the brake applied to both wheels, I should regard a brake applied to one wheel only as within the scope of my invention.

5 What I claim as my invention is—

1. In a mining-machine which embodies a drilling-cylinder and wheels for supporting the same, the combination of a rock-shaft furnished with rollers adapted to run behind 10 the said wheels on the same surface therewith, a brake-dog affixed to said rock-shaft, bars pivotally connecting said shaft with the said cylinder, and a spring applied to said shaft for drawing the brake-dog forward 15 against a supporting-wheel, substantially as herein described.

2. In a mining-machine which embodies a drilling-cylinder provided with trunnions and wheels for supporting the same, the combination of a brake-shaft furnished with rollers to run in rear of the said wheels, a brake on said shaft, bars pivotally connecting said shaft with the cylinder-trunnions, a lever on 20 said shaft and a spring connecting said lever with one of said trunnions for drawing the brake toward the wheels, substantially as herein described.

3. In a mining-machine which embodies a drilling-cylinder provided with trunnions and 25 wheels for supporting the same, the combina-

tion of a brake-shaft and rollers thereon adapted to run on the same surface with said wheels in rear thereof, a brake on said shaft, bars pivotally connecting said shaft with the cylinder-trunnions, a hand-lever on said shaft, 35 a spring connecting said lever with one of the trunnions for pressing the brake to the wheels, and a connection between said lever and the cylinder for limiting the movement of the hand-lever by which the brake is withdrawn 40 from the wheels, substantially as herein described.

4. The combination with the drilling-cylinder and its trunnions and the wheels in which the trunnions are supported, of a rock-shaft and rollers thereon arranged under the rear portions of said wheels, bars by which 45 said shaft is pivotally connected with the trunnions and brake-dogs fixedly attached to said rock-shaft and projecting upwardly 50 therefrom against the lower rear portions of the wheels, substantially as herein described.

In testimony that I claim the foregoing as my invention I have signed my name, in presence of two witnesses, this 28th day of January, 1901.

HENRY C. SERGEANT.
